UNITED STATES PATENT OFFICE

157,439

COMBINED TABLE AND LAMP

Frank M. Scarale, Leominster, Mass.

Application July 27, 1948, Serial No. 147,798

Term of patent 3½ years

(Cl. D33—14)

To all whom it may concern:

Be it known that I, Frank M. Scarale, a citizen of the United States, residing at Leominster, in the county of Worcester and State of Massachusetts, have invented a new, original, and ornamental Design for a Combined Table and Lamp, of which the following is a specification, reference being had to the accompanying drawing, forming part thereof.

The figure is a perspective view of a combined table and lamp, showing my new design.

The characteristic features of my combined table and lamp are shown in full lines in the drawing.

I claim:

The ornamental design for a combined table and lamp, as shown and described.

FRANK M. SCARALE.
